Filed May 21, 1965, Ser. No. 457,712
8 Claims. (Cl. 62—196)

This invention relates to defrosting devices for refrigerating units such as cold storages and freezers and involves an improvement in defrosting devices of the type in which hot refrigerant gas from the compressor is fed into the evaporator of the refrigerating unit.

In general, this hot gas type of defrosting device necessitates, in addition to the refrigerating unit including a motor-driven compressor condenser, capillary tube and evaporator, at least such devices as a solenoid valve assembly (A) for changing the path of hot gas, a switch (B) capable of continuously sensing the evaporator temperature to detect a certain frost temperature appropriate for defrosting operation and a certain defrost temperature at which such operation is to be completed, another switch (C) for manually or automatically starting the defrosting operation, and appropriate wiring connections between these elements A, B and C.

The hot gas type defrosting device in its early stages of development included a series connection of the elements A, B and C, which was arranged in parallel to the compressor circuit. The switch device C employed to start the defrosting operation was one operable manually or automatically to close the associated circuit and also manually or automatically to open the same. Thus, with this early type of defroster, the switch C for starting the defrosting operation is closed when the switch B detecting the frost temperature appropriate for the defrosting operation is closed. The closing of switch C causes the solenoid valve to operate to rush hot refrigerant gas from the compressor into the evaporator thereby starting the defrosting operation. Upon completion of the defrosting operation, the switch B detecting the evaporator temperature is rendered inoperative and accordingly the switch C is opened to stop conveying hot refrigerant gas to the evaporator.

With the above-described defrosting device, the switch B is arranged to close the associated circuit upon detection of the evaporator temperature appropriate for the defrosting operation. Strictly speaking, however, of this circuit-closing operation of switch B, the time when it is operatively closed is not always appropriate to start the defrosting operation. In other words, the switch B is always closed when the evaporator temperature is reduced to a certain frost temperature, such as an extreme low level in general ranging from -15° C. to -20° C., the evaporator is in a state to be defrosted carrying a substantial amount of frost thereon. For example, however, in case the system is operated for rapid cooling immediately after the desired defrosting has been completed, the evaporator temperature may reach an extreme low level because of such rapid cooling to cause closing of the circuit even if no frost is found on the evaporator. Thus, with this defrosting device, if the user fails to open the switch C after the defrosting operation and the evaporator temperature is reduced by any immediate rapid cooling operation of the system, the switch B may possibly be closed again to send hot gas into the evaporator.

One improvement previously made in this type of defroster in an effort to overcome the above deficiency is as follows: For one switch means are provided a diaphragm means for detecting the temperature of the evaporator when completely defrosted and imparting to the switch only a motion in the opening direction and a pushbutton means for imparting to the switch a motion

2

primarily in the closing direction. Further, the switch includes a leaf spring or like biasing means and, once actuated by the diaphragm or push-button means, the switch can never be restored unless it is acted upon by some external force. The above three components are normally brought together in a casing to form an integral device, generally called defrosting thermostat, which is used in combination with an appropriate solenoid valve assembly. This arrangement apparently includes a single switch which is closed by the pushbutton to start the defrosting and opened when the evaporator temperature reaches a defrost temperature at which all the frost produced on the evaporator has been defrosted. It is noted that, after the switch has been opened or restored automatically in response to the evaporator temperature, there is no possibility that hot gas be unnecessarily fed into the evaporator unless the user intentionally operates to restart defrosting.

It is also noted, however, that such defrosting thermostat usable with a defrosting device of the type described should have a physical force in response to the rise and fall of the evaporator temperature. The diaphragm device achieves this purpose. The diaphragm device, however, is itself complicated in structure and function and liable to misoperate. Moreover, the defrosting thermostat includes a pushbutton means and a switch in addition to the diaphragm device, as described hereinbefore, and the three components must be combined to work in coordination. It follows, therefore, that the defrosting device utilizing such thermostat is deficient in that it is complicated in construction just because of its incorporating the thermostat and is not fully reliable in function. Apparently, the same can be said even if a timer instead of the pushbutton means is used for automatically closing the switch.

Also, the defrosting thermostat described is usually arranged in the insulation wall of the refrigerator unit to save space and for operational reasons. Such thermostat arrangement in the insulation is evidently undesirable from the viewpoint of the insulation efficiency of the refrigerator walling. In addition, recent use of polyurethane foam in refrigerator units has realized reduction in thickness of their insulation walls owing to the excellent insulating property of the material, and it is practically impossible to arrange a defrosting thermostat of the type described in the insulation wall of such reduced thickness.

Accordingly, there is an increasing demand for a defrosting device which is designed not to feed any hot gas needlessly into the evaporator after the end of the defrosting operation, is simple in structure and reliable in function, and can be installed in any desired location within the refrigerator unit.

The present invention is intended to provide an improved defrosting device which meets the above demand with success.

As to a solenoid valve assembly, it is well known that it includes a solenoid coil, an armature or plunger and a needle element carried by the armature for opening the bypass conduit to convey hot refrigerant gas to the evaporator. The intensity of magnetic force produced by the solenoid coil which is required to actuate the plunger or armature to the actuated position thereof for opening and closing the associated gas passage, differs in magnitude from that required to hold the armature in its actuated position, i.e., the latter is more or less smaller than the former. The present invention is principally based upon this fact and forms its ingenious application to the defrosting art.

More specifically, the present invention is characterized in that it includes a solenoid valve assembly so designed that the solenoid coil produces, upon closing of a bimetal switch provided for detection of the evaporator tem-

perature appropriate to start defrosting, a magnetic force of an intensity insufficient to effectively actuate the armature but sufficient to hold the armature in its actuated position, and subsequently produces a magnetic force of an intensity sufficient to effectively actuate the armature for a short period of time to open the bypass passage for directing hot gas into the evaporator.

The above and other objects and features of this invention will become more apparent by reference to the following description taken in conjunction with the accompanying drawings, in which:

FIG. 1 is a circuit diagram of one embodiment of the invention;

FIG. 2 is a sectional view of the solenoid valve assembly used in the embodiment shown in FIG. 4;

FIG. 3 is a circuit diagram illustrating another embodiment of the invention;

FIG. 4 is a circuit diagram of a further embodiment of the invention; and

FIG. 5 is a cross section of the solenoid valve assembly used in FIG. 4.

Referring to the drawings, reference numeral 1 indicates a compressor; 2 a condenser; 3 a capillary tube; and 4 an evaporator. These four components are in fluid communication with each other through conduit lines 5a, 5b, 5c, 5d and 5e, as illustrated, to form a refrigerator unit. Thus, the high-temperature high-pressure gaseous refrigerant in the compressor 1 enters the condenser 2, in which the gas releases heat contained therein and then it is liquefied. The liquefied refrigerant is reduced in pressure by passing through the capillary tube 3 and is then vaporized in the evaporator 4 to return to the compressor 1 in gaseous form. As is well known, the liquid refrigerant takes in heat from the environment when it is vaporized, and a refrigerator includes an evaporator for vaporization of liquid refrigerant and arranged in a heat-insulated chamber for the purpose of cooling its interior.

Reference numeral 6 indicates a solenoid valve assembly schematically shown in FIG. 1 with a bypass conduit 7 connected at one end thereof with the solenoid valve assembly and at the other end thereof with the upstream side of the evaporator.

Referring to FIG. 2, which illustrates the details of the solenoid valve assembly, the valve body or casing 8 is formed in its lower portion with a cavity 9 and includes a tubular guide portion 10 which extends vertically upwardly. Formed in the valve casing 8 on its opposite sides are apertures 14a and 14b which communicate with the cavity 9. Also formed in the valve casing 8 at its bottom is an aperture 14c which communicates with the cavity 9 and is opposite to the bottom end of the hollow 13 in the tubular guide portion 10. As shown, these apertures 14a, 14b and 14c fixedly receive conduits 5a, 5b and 7, respectively. The tubular guide portion 10 of the valve casing 8 is covered at its open top by a cap 15, which tightly closes the hollow space 13 in the guide portion and the cavity 9 in the casing body.

A solenoid coil 16 is arranged about the periphery of the tubular guide portion 10 for producing a desired magnetic force when energized. The solenoid coil 16 includes a large number of turns of a wire wound about the cylindrical wall 18 of a hollow toroidal bobbin 17, which is made of an electrically insulating material and includes in addition to the cylindrical wall 18 circular flange walls 19 and 20 extending radially outwardly from the cylindrical wall 18 at its top and bottom. Obviously, the solenoid coil has two terminals, not shown in FIG. 2. An iron yoke 21 is provided to wrap the solenoid coil 16 for the purpose of making uniform the distribution of the lines of magnetic force formed by the solenoid coil 16. The coil 16 and yoke 21 are assembled together in toroidal shape, as apparent in FIG. 2, and the tubular guide portion 10 of the valve body 8 extends upwardly through the central bore of such assembly. A disc spring 22

secures the coil and yoke assembly to the shoulder portion of the valve casing 8.

A hollow plunger or armature 23 has an outside diameter more or less smaller than the inner diameter of the tubular guide portion 10 and is loosely fitted in the hollow 13 of the tubular guide portion 10 defining together with its inner wall 12 a small space therebetween for vertical movement. Thus, when actuated by the solenoid coil, the armature 23 is attracted upwardly. The hollow armature 23 has on its inner wall 24 at the bottom thereof a radially inwardly extending annular restraining flange 25. A needle element 26 has an upper stem portion loosely fitted to the central aperture of the annular flange 25 on the hollow armature and extended into the interior of the armature and has an annular flange 27 at the top of the stem portion in the interior of the hollow armature 23 in axially opposite relation to said restraining flange 25. As the armature 23 rises, the flanges 25 is brought into engagement with flange 27, so that the needle element 26 is raised together with the armature 23. The needle element 26 has a body portion conically shaped at the bottom thereof to form a sharp needle point and formed flat at the top thereof to form annular shoulder 29. When the armature is rendered inoperative, the armature 23 is supported on the needle element 26 with its annular shoulder 29 in abutting engagement with the bottom of the armature 23. As shown, the needle element 26 is disposed opposite to the aperture 14c, formed in the bottom of the valve casing 8, and normally, or when the element 26 is free from any external influence, its sharp bottom end is fitted in the aperture 14c to completely close it at its constricted top end 30.

In the aforescribed refrigeration cycle, the solenoid valve 6 during cooling operation is in the state shown in FIG. 2 with its needle element 26 positioned to close the bypass conduit 7 so that hot gas flowing from the compressor 1 through conduit 5a is allowed to enter conduit 5b. For defrosting the evaporator 4, the solenoid coil 16 is energized to actuate the armature 23 so that the latter is raised carrying the needle element 26 to open the aperture 14c. As a consequence, hot gas from the conduit 5a proceeds into the bypass conduit 7 owing to the pressure difference between the conduits 5a and 5b. The hot gas is effective to defrost the evaporator 4 by passing through conduit 5d.

In the embodiment as described in FIG. 1, a bimetal switch 33, which is rendered operative in accordance with the evaporator temperature, is connected in series with a resistor 34 and a break switch 35 operatively opened. This series connection is connected in parallel with a switch 32.

The solenoid coil 16 of the solenoid valve assembly 6 is connected in series with the parallel connection of the bimetal switch 33 and the switch 32 to an electric power source 31. According to the present invention, the switch 32 is designed to close for a period of time not longer than that required to defrost the evaporator 4 but sufficient such that the solenoid coil may completely actuate the armature either manually or automatically, for example by an electric timer or by counting the number of refrigerator door openings.

In practice, the switch may include an externally arranged pushbutton which, when depressed, is arranged to actuate the solenoid coil.

In case the evaporator temperature falls, the switch 33 is closed when the temperature reaches a level appropriate for defrosting, which is between -15° C. and -20° C. On the other hand, in case the evaporator temperature rises as the defrosting proceeds, the bimetal switch 33 is opened when the evaporator has been completely defrosted, or at approximately 4° C. A resistor 34 is connected in the bimetal switch circuit 33a. Otherwise, when the bimetal switch 33 is closed, the solenoid coil 16 would be energized by the full current flowing through the circuit 16a to produce a substantially large magnetic

force effective to actuate the armature 23. It would follow, therefore, that the armature 23 be actuated to open the bypass conduit 7 each time the bimetal switch 33 is closed. This is obviously undesirable and can be prevented by the insertion of the resistor 34 in the bimetal switch circuit 33a. According to this invention, such resistor is specifically selected to limit current flow through the circuit 33a and solenoid coil circuit 16a so that only a magnetic force is produced by the solenoid coil 16 with an intensity which is insufficient to actuate the armature 23 but sufficient to hold the armature at the actuated position thereof once it is actuated. Thus, the resistor 34 should be designed, by taking the number of turns of the solenoid coil 16 and the size of armature 23 into account, to limit the current flow through the solenoid coil so that only a magnetic field is produced with the predetermined intensity.

The following is a description of the defrosting operation of the embodiment described in FIG. 1.

When no frost is found on the evaporator 4, there is no current flow through the bimetal switch circuit 33a or solenoid coil circuit 16a. During use of the refrigerator unit, as frost is formed on the evaporator in an increasing amount, the temperature of the evaporator is reduced and reaches a level of from -15° C. to -20° C., accordingly the bimetal switch 33 is closed to cause an electric current flow through the solenoid coil circuit 16a by way of bimetal switch circuit 33a. The current is limited by the resistor 34, as described hereinbefore, so that the magnetic force produced by the solenoid coil 16 is not sufficient to actuate the armature 23 to any effective extent and no defrosting occurs. For defrosting operation, it is only necessary for the user to close the switch 32 to render the solenoid coil operative when the user, observing the frosted state of the evaporator, feels the need of it being defrosted. In this manner, the solenoid coil circuit 16a is fed with a full current flowing directly from the power source 31, but not by way of the bimetal switch circuit 33a, with the result that a substantial magnetic force is formed in the solenoid coil 16. The magnetic force is effective to actuate the armature 23 vertically upwardly within the tubular guide portion 10 of the valve casing 8. Thus, the armature 23 carries with it the needle element 26 vertically upward to open the bypass conduit 7. Consequently, hot gas from the compressor 1 is allowed to flow through conduit 5a into bypass 7 to effect defrosting of the evaporator.

It is to be noted here that the switch 32 is designed to operate for a limited period of time independently of the other defroster components. Namely, the switch acts to reopen the solenoid coil circuit shortly after the armature 23 has been completely actuated and thus acts to close the circuit for the sole purpose of actuating the armature. After the opening of the solenoid coil circuit 16a including switch 32, the solenoid coil is fed with a reduced current by way of the bimetal switch circuit 33a to hold the armature 23 in its actuated position. This means that the defrosting operation is continued even after the opening of switch 32. After the evaporator 4 has been defrosted completely with its temperature raised, the bimetal switch 33 is also opened and thus all the circuits are de-energized. As the result, the armature 23 and needle element 26 of the solenoid valve assembly 6 are restored to their normal position closing the bypass conduit 7 to complete the defrosting cycle.

During defrosting, if it is desired to stop the defrosting operation, it is only required to open the switch 35 temporarily. By doing this, the armature 23 is restored from its activated position to its normal one to close the bypass conduit 7 and the flow or hot gas to the evaporator 4 is interrupted.

In the above-described embodiment, the series connection of the bimetal switch 33 and resistor 34 is connected in parallel to the switch 32. Apparently, however another arrangement is that the resistor 34 alone is con-

nected in parallel with switch 32 and arranging the bimetal switch 33 and the solenoid coil are connected in series therewith, as illustrated in FIG. 3 is also operable in this invention.

FIGS. 4 and 5 illustrate another embodiment of the present invention. As shown, this embodiment employs a solenoid coil means 16, which includes double wound primary and a secondary solenoid coils 36 and 37, respectively. The primary coil 36 together with bimetal switch 33 and switch 35 is connected to a power source 31 in series while the secondary coil 37 is connected to the same together with the switch 32, the two coils being in parallel with each other. One example of the solenoid valve assembly employing such double-wound solenoid means is shown in FIG. 4, which illustrates a primary coil 36 wound about a secondary coil 37.

The number of turns of the primary and secondary solenoid coils is specified as follows. Namely, the primary coil 36 includes a number of turns which produces a magnetic force of an intensity insufficient to actuate the armature 23, which carries needle element 26 for opening but closing the bypass conduit, and sufficient to hold the armature in its actuated position while the secondary coil 37 includes a number of turns which produces a magnetic force with an intensity which is by itself or, when combined with the field intensity caused by the primary coil 36, effective to actuate the armature 23.

The defrosting operation of this embodiment is as follows.

As long as no frost is found on the evaporator 4, there occurs no current through the primary or secondary solenoid coil circuits 36a or 37a. As frost is formed on the evaporator in an increasing amount, its temperature is reduced, and, when it reaches a level of from -15° C. to -20° C., the bimetal switch 33 is closed to energize the primary solenoid coil 36, which produces a magnetic force with intensity which is insufficient to actuate the armature 23 for starting defrosting. On this occasion, if defrosting is required, it is only necessary to close the switch 32 so that in addition to the primary solenoid coil 36, the secondary solenoid coil 37 is energized and now both the primary and secondary solenoid coils 36 and 37 produce a magnetic force. The magnetic force formed by the secondary solenoid coil 37 alone or combined with the force formed by the primary solenoid coil 36 is sufficient to effectively actuate the armature 23 and start defrosting. Obviously, the switch 32 is arranged to be operated independently of the other defroster components to close the circuit for a short period of time, as described hereinbefore, and the armature 23 is actuated when the switch 32 and the bimetal switch 33 are closed and is held in its actuated position by the primary solenoid coil 36 after the switch 32 is opened. The defrosting operation is completed when the bimetal switch, sensing the evaporator temperature, opens.

With this embodiment, it is possible to indicate whether the defrosting is being effected or not by a parallel connection of an electric lamp 38 with the secondary solenoid coil 37 (FIG. 4). The lamp 38 is first lighted by closing the switch 32 and subsequently by the electro-motive force induced in the secondary solenoid coil 37 by energization of the primary one.

As apparent from the foregoing description, the switch 32, when operative renders the solenoid coil operative to actuate an armature carrying a needle element provided in the bypass conduit, is only required to render the solenoid coil operative for a short period of time, and thus is of the type operable independently of the other defroster components to close for a short period of time. This switch is obviously in its open position when any switch operable in response to the evaporator temperature is again rendered operative during normal refrigerating operation just after completion of the defrosting

operation, and thus effectively eliminates the danger of the armature being actuated again for defrosting operation.

Also, since the switch provided for actuation of the armature to start defrosting is of the type operable independently of the other defroster components, as described hereinbefore, there is no need of employing any means for mechanically transmitting the change of the evaporator temperature to the switch. Thus, a bimetal switch may be used just for means directly responding to the evaporator temperature and thus any diaphragm device conventionally used in the defroster of the character described can be dispensed with, eliminating any labor and cost previously required to assemble such defroster elements as the diaphragm device, switch and pushbutton means. Thus, according to the present invention, a defrosting device is provided which as a whole is simplified in structure and function and reliable in operation.

In addition, the defrosting device according to the present invention does not necessitate any thermostat which is relatively voluminous and has only a limited freedom of location, and thus has no adverse effect upon the insulation efficiency of the refrigerator walling and, with the solenoid valve, switch for starting the defrosting operation, bimetal switch and other components connected by wiring, can be installed freely at any location.

Although a few embodiments of the present invention have been illustrated and described, it will be apparent to those skilled in the art and various changes and modifications may be made therein without departing from the spirit of the invention or from the scope of the appended claims.

What is claimed is:

1. A defrosting device in combination with a refrigerating unit including a compressor, condenser, capillary tube and evaporator in fluid communication, comprising bimetal switch means operatively closed in response to the temperature of the evaporator of the refrigerating unit, a solenoid valve assembly connected with said compressor, a bypass conduit connected at one end thereof to said solenoid valve assembly and at the other end thereof to the upstream side of the evaporator; said solenoid valve assembly including a solenoid coil associated with said bimetal switch means, an armature arranged in said solenoid coil and reciprocably moved by said solenoid coil, a needle element carried by said armature for operatively opening and closing said bypass conduit, said solenoid valve assembly being designed to produce when said bimetal switch means is closed a magnetic force with an intensity insufficient to actuate said armature and sufficient to hold the armature in an actuated position; and switch means associated with said solenoid coil and independently rendering said solenoid coil operable to produce an additional magnetic force sufficient to actuate the armature in said solenoid coil.

2. A defrosting device according to claim 1, which further comprises a resistor element connected in series with said bimetal switch means, the series connection of said resistor element and said bimetal switch means being connected in parallel with said switch means, and the parallel connection of said series connection and said switch means being connected in series with said solenoid coil to an electric power source for energizing said solenoid coil.

3. A defrosting device according to claim 2, which further comprises second switch means inserted in series in the series connection of said resistor element and said bimetal switch means, said second switch means rendering said solenoid coil inoperative such that said armature closes said bypass conduit.

4. A defrosting device in combination with a refrigerating unit including a compressor, condenser, capillary tube and evaporator in fluid communication, comprising a solenoid valve assembly connected with said compressor and including a solenoid coil, an armature axially movably positioned in said solenoid coil, a needle element

carried by said armature, a bypass conduit connected at one end thereof to said solenoid valve assembly and at the other end thereof to the upstream side of the evaporator, said needle element opening and closing said bypass conduit in response to the movement of said armature, bimetal switch means activated in response to the temperature of the evaporator, a resistor element connected in series with said solenoid coil to an electric power source, said solenoid coil producing upon closing of the bimetal switch means, a magnetic force with an intensity insufficient to actuate said armature and sufficient to hold the armature in an actuated position, and a switch means connected in parallel with said resistor element for bypassing the resistor element and independently causing said solenoid coil to produce an additional magnetic force to actuate said armature.

5. A defrosting device according to claim 4, which further comprises second switch means connected in series with said resistor element in the parallel connection of said resistor element and said first mentioned switch means, said second switch means rendering said solenoid coil inoperative such that said armature closes said bypass conduit.

6. A defrosting device in combination with a refrigerating unit including compressor, condenser, capillary tube and evaporator in fluid communication, comprising a solenoid valve assembly connected with the hot gas outlet of said compressor, a bypass conduit connected at one end thereof to said solenoid valve assembly and at the other end thereof to the upstream side of the evaporator, said solenoid coil means valve assembly including solenoid coil means, and armature axially reciprocably movable within said solenoid valve assembly, a needle element carried by said armature and for opening and closing said bypass conduit, said solenoid coil means including a primary solenoid coil to produce a magnetic force with an intensity insufficient to actuate said armature and sufficient to hold the armature in its actuated position and a secondary solenoid coil to produce an additional magnetic force with an intensity at least sufficient to actuate said armature, bimetal switch means connected in series with said primary solenoid coil, and responsive to the temperature of the evaporator, and independently operable switch means connected in series with said secondary solenoid coil to cause said secondary coil to activate said armature.

7. A defrosting device in combination with a refrigerating unit including compressor, condenser, capillary tube and evaporator in fluid communication, comprising:

a bypass conduit for bypassing said condenser and said capillary tube for conveying hot refrigerant gas from said compressor to the upstream side of said evaporator,

a solenoid valve assembly including a solenoid coil, an armature actuated by said solenoid coil and a valve element carried by said armature for opening said bypass conduit when said armature is actuated, bimetal switch means for sensing the temperature of said evaporator such that when the evaporator temperature drops under a predetermined frost temperature said bimetal switch means closes until the evaporator temperature exceeds another predetermined defrost temperature, and switch means for operating independently of said bimetal switch means at least for a period of time sufficient for completion of the actuation of said armature,

said solenoid coil being provided to produce a magnetic force with an intensity insufficient to actuate said armature but sufficient to hold the armature at the actuated position thereof when said solenoid coil is energized by the bimetal switch means and with another intensity sufficient to actuate said armature when said solenoid coil is energized by both the switch means and the bimetal switch means whereby the bypass conduit remains opened independently of the op-

eration of said switch means as long as said bimetal switch means remains operative when both the bimetal switch means and the switch means have been previously activated.

8. A defrosting device according to claim 7, which further comprises second switch means for deactivating the solenoid coil to release the armature and enable the valve element to close the bypass conduit.
